UNITED STATES PATENT OFFICE.

GEORGE H. SHRODES, OF LOS ANGELES, CALIFORNIA.

ARTIFICIAL LIMB.

Application filed July 6, 1925. Serial No. 41,566.

My invention relates to improvements in the lower portion of the leg and includes the foot therewith and consists in the scientific application of mechanism which will function in the same manner as the natural parts which they are designed to replace. The object thereof is to produce simple and cheap and efficient parts which when assembled will function as do the natural parts which they replace and to produce a device that if a portion thereof becomes broken or worn to such an extent that such portion is objectionable the same can be easily replaced with a new portion and in which repairs can be made by an unskilled workman.

In the drawings forming a part of this application Fig. 1 is a side elevation. Fig. 2 is a section on the line 2—2 of Fig. 1. Fig. 3 is an enlarged detail showing the manner of connecting the leg wires to the upper band 10. Fig. 4 is a section on the line 4—4 of Fig. 1. Figs. 5—8 are sectional details showing the construction of certain of the parts of my device.

Referring to the drawings 10 is the top band and may be called the knee band. 11 is the lower band of the leg and may be called the ankle band. The intermediate bands 12 and 13 may be called the stiffening bands. These bands are preferably made of aluminum as it is both strong and light.

Running from band 10 to band 11 and suitably and detachably connected to both bands are the leg wires 14 of which there may be any desired number. These wires are preferably made from piano string wire and they are bent to conform to the form of the leg which they are to replace. Wires 14 are secured to bands 12 and 13 by clamping member 15, which members are preferably connected to the bands by screws 16 so that in case a wire breaks another wire can be easily substituted for the broken wire. Integral with band 10 are side lugs 17 which extend downwardly to and are connected to band 13 by rivets 18. The size and length of lugs 17 is governed by the size and length of the limb that is to be replaced. Band 11 has on each side thereof

downwardly projecting foot lugs 19 the lower ends of which are bifurcated. Lugs 19 are connected to upwardly projecting sole lugs 20 by ankle bolt 21. Lugs 20 are preferably integral with sole plate 22 which has a toe portion 23. This toe portion is preferably hollow for lightness and is integral

with the sole which is preferably made of aluminum. The rear portion of the rear wall of the toe is a little lower than the front portion and in this lower portion of 60 said wall is received the front ends of what I term the instep wires 24 of which there may be any desired number. I have shown three as I consider that number sufficient for the average foot but there may be a 65 greater or less number as desired. As shown in Figs. 4, 5 and 7 the ends of wires 24 are bent at right angles to the main portion and such ends enter holes 25 in the back wall 26 of the toe (see Fig. 5) and are held 70 therein by a plate 27 which is connected to wall 26 by screws 28. The other ends of wires 24 are bent angularly to the body thereof and enter sockets 29 in band 11 as best shown in Fig. 5 and are held positioned 75 therein by plates 30 which are detachably connected to band 11 by screws 31. Plates 30 also hold the lower ends of the front leg wires 14. Intermediate the ends thereof and about the center wires 24 are coiled as at 80 32 to give them greater resiliency. The rear or heel end of sole 22 projects upwardly a short distance as best shown in Fig. 5 and forms a heel lug 33 in which are sockets 34. In these sockets are received the out-turned 85 ends of heel wires 35. The upper ends of wires 35 are out-turned and enter sockets in band 11 and are held therein by plate 30 which plate holds the lower ends of the rear leg wires 14 detachably secured to band 11. 90 Screws 31 connect plate 30 to band 11. Intermediate the ends thereof wires 35 are coiled to give greater resiliency. An instep plate 39 is secured to the front portion of sole 22 by screws 40. A heel plate 41 is secured to the rear portion of sole 22 by screws 42. Sole 22 may be provided on its upper surface with longitudinal stiffening lugs 43 and with a transverse heel lug 44. Sole lugs 20 are provided with stop pins 45 100 that project outwardly between the bifurcated ends of lugs 19 to limit the relative movement of the foot. This relative movement is also limited by the engagement at the front of plate 39 with band 11 and at 105 the rear by engagement of plate 41. Where bolt 21 passes through I provide a bushing 46 which has a diagonal slit 47 therein in which a lubricant can be placed if desired. On the ends of bolt 21 I provide nuts 48 110 which are threaded right hand and in the ends of bolt 21 are sockets 49 which are

threaded left hand. A bolt 50 screws into each of these sockets and the heads 51 project over nuts 48 and engage lugs 17 and thereby lock nuts 48 on bolt 20. Heads 51 are fabricated to give a close resemblance to the projecting ankle bones.

By this construction it will be seen that in case of a break in any of the parts a new part can readily be inserted. The action of 10 the foot lugs rocking on the leg lugs with the instep and heel springs to hold the foot in normal position gives an almost perfect natural action.

Having described my invention I claim—

- 15 1. An artificial lower limb comprising in combination knee and ankle bands; a plurality of wires forming the lower limb contour, said wires being detachably connected at the top to the knee band and at the bottom 20 to the ankle band; lugs projecting downwardly from the ankle band; a sole plate; lugs projecting upwardly from the sole plate; means to connect the sole lugs and ankle lugs; a resilient connection from the toe portion 25 of the sole plate to the ankle band; a resilient connection from the heel portion of the sole plate to the ankle band; an instep plate connected to the sole plate and a heel plate connected to the heel portion of the sole plate.

- 30 2. An artificial lower limb comprising in combination knee and ankle bands; downwardly projecting lugs from said bands, said bands having sockets therein; a plurality of 35 wires having out-turned ends, said ends being adapted to enter the sockets in said bands; means connected to said bands adapted to hold the ends of said wires in said sockets; a sole plate having a heel portion, an instep portion and a toe portion; lugs projecting upwardly from said plate; means to pivotally connect said last lugs with the ankle band lugs; resilient instep 40 wires connected to said ankle band and to 45 the rear portion of the toe of the sole plate;

resilient heel wires connected to said ankle band and to said heel portion of the sole plate; said instep and heel wires being detachably connected to the co-acting parts; and an instep plate and a heel plate connect- 50 ed to the sole plate.

3. An artificial lower limb comprising in combination knee and ankle bands, said bands having sockets therein and downwardly projecting lugs, the ankle band lugs having their lower ends bifurcated; a plurality of wires having outturned ends, said ends being adapted to enter the sockets in said bands; detachable means to hold said ends in said sockets; a strengthening band intermediate 60 said knee and ankle bands, and connected to the bottom portions of the lugs of the knee band; means to detachably connect said wires with said strengthening band; a sole plate having a heel portion, an instep portion and a toe portion; lugs projecting upwardly from said sole plate; a bolt projecting through the sole plate lugs and the ankle band lugs, said bolt rockably connecting said lugs; bushings on said bolt and 65 within said sole plate lugs; nuts on said bolt to hold the same from separating from said lugs; bolts having heads screwed into the ends of the bolt connecting the lugs; the heads of said last bolts surrounding the nuts 70 on the first bolt and forming lock nuts, resilient instep wires, each having a coil therein intermediate its ends detachably connected to the ankle band and to the toe portion of the sole plate; resilient heel wires each 75 having a coil therein intermediate its ends detachably connected to said ankle band and to the heel portion of the sole plate; and instep and heel plates connected to said sole plate. 85

In witness that I claim the foregoing I have hereunto subscribed my name this 27th day of June 1925.

GEO. H. SHRODES.
